[57] CLAIM

The ornamental design for display rack, as shown and described.

DESCRIPTION

FIG. 1 is an isometric view of a display rack embodying my new design, the cylinders being shown in broken lines for illustrative purposes only;

FIG. 2 is a front elevational view of FIG. 1;

FIG. 3 is a top plan view of FIG. 1;

FIG. 4 is an isometric view of a second embodiment of the design of FIG. 1.

FIG. 5 is a reduced top plan view of a third embodiment of the design of FIG. 1;

FIG. 6 is a reduced isometric view of a fourth embodiment of the design of FIG. 1;

FIG. 7 is a top plan view of FIG. 6.

The only difference in the embodiments of FIGS. 4 through 7 is the arrangement and number of the individual display racks.
